IMPRINTER

William P. Barbour, Alexandria, Va., assignor to Control
Data Corporation, Washington, D.C., a corporation of Delaware

Filed Apr. 22, 1969, Ser. No. 16,845

Term of patent 14 years

Int. Cl. D18—02

U.S. Cl. D64—11

Fig. 2

Fig. 3

Fig. 4

FIG. 1 is a perspective view of an imprinter showing my new design.

FIG. 2 is a side view, and the side not shown presents a substantially similar appearance.

FIG. 3 is an end view as seen from the left of FIG. 2. FIG. 4 is an end view as seen from the right of FIG. 2.

I claim:

The ornamental design for an imprinter, as shown and described.
